UNITED STATES PATENT OFFICE.

MOSES G. FARMER, OF ELLIOT, MAINE.

TELEPHONE-TRANSMITTER.

SPECIFICATION forming part of Letters Patent No. 380,427, dated April 3, 1883.

Application filed September 14, 1887. Serial No. 249,622. (No model.)

To all whom it may concern:

Be it known that I, MOSES G. FARMER, a citizen of the United States, residing at Elliot, in the county of York, State of Maine, have invented a new and useful Improvement in Telephone-Transmitters, which improvement is fully set forth in the following specification and accompanying drawings.

My invention relates to improvements in telephone-transmitters of the Hunnings type; and it consists in a novel arrangement of the electrodes within the carbon powder, and in certain details of construction hereinafter described, and particularly pointed out in the claims which follow this specification.

In an application filed by me in the United States Patent Office April 14, 1887, bearing Serial No. 234,795, I have disclosed a novel form of telephone-transmitter of this type having rigid fixed electrodes, with a diaphragm sustaining the carbon powder against or upon the electrodes. In the invention I now propose to disclose I retain the carbon powder in a case similar to that shown in my prior application between two metallic plates and arrange two or more flexible perforated electrodes in close proximity to each other within the mass of loose powder.

My invention will be better understood by referring to the accompanying drawings, in which—

Figure 1 is a plan view of my improved telephone-transmitter with the diaphragm removed, so as to show the electrodes. Fig. 2 is a cross section on line $x-x$, Fig. 1. Fig. 3 is a plan view showing the diaphragm in place. Fig. 4 is an obverse plan view of the instrument, showing the connections and binding posts.

Similar letters of reference indicate corresponding parts in the several figures.

Referring to the drawings, A is the body of the instrument, of gutta-percha or analogous material, of cup form, as shown.

B B' are two thin metal plates, the latter fitting snugly in the bottom of the cup and the former adapted to be held firmly in place over the carbon or comminuted powder, M, as shown, by the ring D, screw-threaded into the body of the instrument.

C C C' C' are four perforated elastic metallic electrodes adapted to fit, as shown, the inner

contour of the retaining-cup A, and held in place in the body of the carbon powder by the binding-screws N N, &c., having metal heads 55 E E E' E' and metal washers H H, &c.

W W are insulating-washers, of mica or like material, adapted to insulate the plate B' from the metal binding-posts connected to the electrodes C C'. Each pair of electrodes C C C' C' 60 has a pair of metal washers, W' W', on the under side, connecting the electrodes electrically with the binding-posts N N and serving to sustain the electrodes in submerged condition in the comminuted powder, but insulated from 65 the lower plate or diaphragm B' by insulating washers, as shown.

N N are binding-posts, four in number, connected to the four electrodes E E E' E' and having binding-screws F F F' F'.

M is the comminuted conducting-powder, held in place by the diaphragm B and back plate B'.

The electrodes are connected in pairs, E E being connected to the minus-pole of battery, 75 as shown in Fig. 4, by wire w^2 and binding-screws F F, while E' E' are similarly connected to the plus-pole by wire w^1 and binding-screws F' F'.

I find that with the metal front and back 80 plates, both of which act as diaphragms, I increase the conductivity of the instrument and get increased effects therefrom.

The retaining-ring D is secured in place by means of an instrument entering the holes e e.

Having thus described my invention, what I claim as new, and desire to secure by Letters Patent, is—

1. A telephone-transmitter having comminuted powder retained between two conducting-plates, and two or more electrodes resting in the body of the powder between the plates, substantially as described.

2. A telephone-transmitter having two or more electrodes, in combination with front and 95 back plates of conducting material, and carbon powder or analogous material located between said plates and entirely surrounding the electrodes, substantially as described.

3. The combination, in a telephone-transmitter, of a front and a back plate of conducting material, with two or more fixed perforated electrodes surrounded by carbon or analogous conducting-powder and located be-

tween the front and back plates, substantially as described.

4. In a telephone-transmitter, the combination of a retaining-case having a back plate of 5 metal located inside said case, two or more electrodes entirely surrounded by carbon or analogous conducting-powder, and an additional metallic plate for holding the carbon powder in place, substantially as described.

10 5. In a telephone, a retaining case or cup, in combination with two metal plates, one located in the base of the cup and the other resting upon carbon powder contained in said cup, with two or more electrodes embedded in the 15 carbon powder, and a retaining-ring adapted to hold the outer plate against the carbon powder, substantially as described.

6. In a telephone-transmitter, a non-conducting cup having two or more binding-posts

extending through the base of the cup and connected to two or more electrodes embedded in carbon powder, in combination with two metal plates adapted to hold such carbon powder within the cup, and a retaining-ring for holding the parts in contact with each other, substantially as described.

20 25 7. In a telephone, the combination of a retaining-cup having a metal plate in its interior, with two or more electrodes embedded in carbon powder located within said cup, with an exterior retaining metal plate, and a retaining-ring for holding said parts in connection, substantially as described.

MOSES G. FARMER.
